FLOW RESTRICTOR

John W. Carlson, Chicago, Ill.

Application November 5, 1946, Serial No. 707,849

2 Claims. (Cl. 138—45)

1

This invention relates in general to flow restrictors or discharge devices which are particularly adapted to restrict the flow of liquids under pressure such as carbonated water.

Devices of this character have been used heretofore for dispensing carbonated liquids in many different places such as soda fountains and vending machines capable of dispensing carbonated beverages. While the discharge device disclosed herein is particularly adapted for use on such a carbonated beverage vending machine, it is by no means limited to such use.

It is the present practice in machines of this character to maintain a volume of saturated or substantially saturated aqueous solution of carbon dioxide to be discharged into a receptacle. This carbonated liquid is maintained at a high pressure and usually a low temperature. One of the problems which is presented in dispensing a carbonated liquid is the necessity of discharging the solution from its high pressure to atmospheric pressure fast enough for practical purposes and yet slow enough to prevent excessive agitation and turbulence which results in a loss of gas from the liquid. Furthermore, fine particles of foreign matter may become deposited in ordinary discharge devices tending to clog the passages and thereby reduce the efficiency thereof.

It is common practice to employ some means for disrupting the impact of the issuing solution. Such means usually includes a stationary member to receive the impact of the solution under pressure which distributes the liquid in a spray. This has been found to be unsatisfactory in actual practice not only because of the high rate of gas loss, but also because the small passage which distributes the solution in a spray has a tendency to become clogged due to the inevitable presence of fine particles of foreign matter. Such clogging necessitates removal of the device for cleaning.

In my present invention I have been able to overcome the various disadvantages mentioned above by providing a structure which will not only retain a high gas content in the issuing solution but which also will be self-cleaning, thereby avoiding any necessity for complete removal of the device due to clogging.

One of the principal objects of the present invention is to provide a discharge device for restricting the flow of a fluid under pressure, such as carbonated water, which will minimize gas loss and which has self-cleaning characteristics.

Another object is to provide a flow restrictor for discharging fluids such as carbonated water

wherein the impact member against which the fluid flows is movable.

A further object is to provide a flow restrictor for discharging fluids such as carbonated water wherein the impact member against which the fluid flows is movable under the pressure of the fluid to form a restricted opening which is self-cleaning and which effectively reduces the velocity of flow without an undue agitation or turbulence thereof.

Still another object is to provide a flow restrictor for discharging fluids such as carbonated water wherein the impact member against which the fluid flows is movable under the pressure of the fluid to form a restricted opening, whereby the initial discharge of fluid will have a cleaning effect thereon before the opening becomes fully restricted.

A still further object is to provide a simple and efficient flow restrictor for discharging liquids under pressure such as carbonated water wherein a body is provided in two sections and spaced apart to provide a cavity within which an impact member may move under pressure of the incoming liquid whereby the initial onrush of liquid will clean or flush the cavity, after which the force of the liquid will move the impact member to restrict the cavity and the flow of liquid therethrough.

Other objects and advantages of the invention will become apparent upon reading the following description taken in connection with the accompanying drawing in which:

Fig. 1 is a plan view of the flow restrictor;

Fig. 2 is a longitudinal vertical section therethrough showing the impact member in its normal position; and

Fig. 3 is a fragmentary sectional view similar to Fig. 2 showing the impact member in its restricted position under pressure of the incoming liquid.

The flow restrictor of the present invention is designed as a simplified form and as an improvement over the devices disclosed in the co-pending application of Ernest L. Wolf, Serial No. 700,602, filed October 2, 1946, and my co-pending application, Serial No. 707,850, filed November 5, 1946. Briefly described, the present invention consists of a body portion preferably formed of two sections which are so located as to provide a cavity therebetween and within the body. One section has an inlet and the other is provided with an outlet, each connected or forming a junction with the cavity. An impact member, preferably in the form of a circular disc, is movably mount-

ed within the cavity and yieldable means normally holds the impact member against one side of the cavity. The yieldable means is designed to be overcome by pressure of the incoming liquid so that the impact member will be urged toward the other side of the cavity thus forming a restricted passage for the flow of liquid therethrough. By having the passage through which the liquid flows normally open a greater distance when the device is not in use than when it is restricted and in use, the initial surge of liquid under pressure will flush the cavity, after which it becomes fully restricted and permits the liquid to flow therethrough with a minimum loss of gas.

Referring now more particularly to the drawing and specifically to Fig. 2, it will be seen that the main body of the device is composed of two sections, generally indicated by the numerals 2 and 4, which may be threadedly connected together as shown at 6. An annular gasket 8 is preferably disposed between the outer contacting surfaces of the two sections to thereby provide a seal against the loss of any liquid.

When the two sections are connected together as shown, there will be provided a space or cavity 10 between the two sections, which cavity may be said to be bounded at its edges by the inner surface 12 of the section 2 and at one side thereof by the inner surface 14 of the section 4 and at its other side by the inner surface 16 of the section 2 which extends at substantially right angles to the surface 12 thereof.

The section 2 is provided with a threaded end 18 for purposes of connection with a source of liquid supply under pressure, such as carbonated water. This end has an inwardly extending opening 20 to provide an inlet for the liquid. Within this inlet or opening 20, a tubular member 22 is located having its inner end substantially flush with the surface 16 of the section 2. The tubular member 22 is provided with a plurality of axially extending spaced apart passages 24 to enable the incoming liquid to pass through the inlet 20 into the cavity 10.

A plunger or stem 26 extends inwardly through the tubular member 22 and at its inner end is threadedly engaged with or otherwise suitably secured to the impact member 28 which is of substantially the same configuration as the cavity 10. If this cavity is circular, then the member 28 is also circular and is of a thickness substantially less than the height of the cavity 10. The diameter of the impact member 28 is slightly less than the width of the cavity so as to provide an annular space 30 between the impact member and the inner surface 12 of the section 2.

The plunger 26 is provided at its outer end with a large head 32, and a coiled compression spring 34 surrounds the plunger 26, bearing at one end against the under side of the head 32 and at its other end against the tubular member 22. Thus it will be evident that the force of the spring 34 will normally maintain the impact member against one side of the cavity 10 and preferably against the inlet side thereof. The section 4 of the body portion is provided with an elongated centrally disposed passage 35 which comprises the outlet of the device. The inner end of the outlet connects with the opposite side of the cavity 10 so that liquid under pressure from the inlet after movement of the impact member toward the opposite side, will be directed to the outlet through the passage 30 and the opposite side of the cavity 10.

It is, of course, necessary that some limiting

means be provided to prevent the impact member from closing the outlet and for this purpose I provide a plurality of spaced apart stop members 36 in the form of elongated screws extending from the outer side of the section 4 through to the cavity 10. These stop members are adjustable in order to regulate the distance through which the impact member 28 moves. It will be noted that the inner ends of these stop members 36 extend 10 beyond the inner surface of the section 4 and a short distance into the cavity 10.

In the operation of the device, liquid such as carbonated water will be caused to flow through the inlet 20 and the passage 24 against the impact member 28. The initial surge of the incoming liquid will immediately force the impact member toward the opposite side of the cavity 10, but before the impact member has reached its maximum distance, some of the incoming liquid will have passed through the space 30 around the periphery of the member 28 and to the opposite side of the cavity 10 thus flushing out the cavity and carrying away any foreign matter which might have become lodged therein. Immediately 15 after this initial surge, the force of the liquid will move the impact member against the ends of the stop members 36 to its position as shown in Fig. 3. It will thus be evident that the passage through which the liquid passes has become 20 restricted so that the liquid at this point flows from the inlet through the passage 38 formed between the impact member and the inner surface 16 of the section 2, through the passage 30 and into the opposite side of the cavity 10 to the outlet 35. This manner of self-cleaning and 25 restricting the flow of fluid is such as to maintain a high gas content within the liquid at all times.

Any suitable means can be provided for properly dispensing the liquid from this device and 30 one form illustrated herein comprises a suitable spout 40 adapted to be received within the outlet 35, which spout has a ring 42 secured thereto provided with an annular shoulder 44 against which a lock nut 46 is adapted to bear. The lock 35 nut may be threadedly secured as at 48 to a suitable projection on the body section 4 to thus secure in place the spout 40.

By the use of the present invention it has been found in actual practice that the gas content of 40 carbonated liquids remains very high after dispensing, which is extremely advantageous over devices of this character heretofor known. Furthermore, the service man in attending a beverage vending machine wherein this device is used 45 finds it seldom necessary to disassemble the device for cleaning purposes because of the efficient functioning of the self-cleaning characteristics thereof.

From the foregoing description it will be evident 50 that I have provided a novel flow restrictor or discharge device particularly useful in the dispensing of carbonated fluids from a vending machine or other dispensing apparatus, which device is self-cleaning, thus avoiding the necessity for frequent disassembly of the device by a service man.

It will be evident that changes may be made 55 in the form, construction and arrangement of parts from those disclosed herein without departing in any way from the spirit of the invention or sacrificing any of the attendant advantages thereof, provided, however, that such changes fall within the scope of the claims appended hereto.

Having thus described my invention what I

Claim as new and desire to secure by Letters Patent of the United States is:

1. A self-cleaning carbonated liquid flow restrictor comprising a body having an inlet and an outlet, a cavity within said body connecting said inlet and outlet, an impact member movably mounted within said cavity, and yieldable means normally holding said impact member against the inlet side of said cavity, whereby the initial surge of liquid from the inlet will have a flushing action, after which the impact member will be moved toward the outlet side of the cavity under pressure of the incoming liquid.

2. A self-cleaning carbonated liquid flow restrictor comprising a body having an inlet and an outlet, a cavity within said body connecting said inlet and outlet, an impact member movably mounted within said cavity, yieldable means normally holding said impact member against one side of said cavity, whereby the initial surge of liquid from the inlet will flush the cavity, after which the impact member will be moved toward the opposite side of the cavity under pres-

sure of the incoming liquid, to thereby restrict the flow thereof through the cavity, and adjustable stop means extending axially of said impact member and spaced uniformly around said opposite side of the cavity to limit the restricting movement of said impact member.

JOHN W. CARLSON.
